(57) **CLAIM**

he ornamental design for an imaging device, as shown and described.

DESCRIPTION

FIG. 1 is a front left perspective view of an imaging device in accordance with our new design;

FIG. 2 is a front right perspective view of the imaging device shown in FIG. 1;

FIG. 3 is a rear right perspective view of the imaging device shown in FIG. 1;

FIG. 4 is a rear left perspective view of the imaging device shown in FIG. 1;

FIG. 5 is a front elevational view of the imaging device shown in FIG. 1;

FIG. 6 is a rear elevational view of the imaging device shown in FIG. 1;

FIG. 7 is a left-side elevational view of the imaging device shown in FIG. 1;

FIG. 8 is a right-side elevational view of the imaging device shown in FIG. 1;

FIG. 9 is a top plan view of the imaging device shown in FIG. 1; and,

FIG. 10 is a bottom plan view of the imaging device shown in FIG. 1.

Broken lines and unshaded portions contained within broken lines depict portions of the imaging device that form no part of the claimed design.
